AUTOMOBILE DOOR LATCH

Application filed May 24, 1926. Serial No. 111,202.

This invention relates more particularly to a vehicle door latch adapted to be latched and unlatched from the interior of the vehicle without the use of a key by merely operating the inner handle of the door latch, thereby providing a latch with which all but one of the doors of a closed vehicle may be equipped to permit said doors to be latched and unlatched only from the interior of the vehicle, while the remaining door may be equipped with a door latch of a type similar to the other door latches with the exception that said last mentioned door is provided with an externally accessible key lock mechanism adapted to permit the last door to be unlocked from the exterior of the vehicle.

It is an object of this invention to provide an automobile door latch adapted to have the outer handle latch bolt retracting mechanism moved into an inoperative position by the operation of the inner handle mechanism in a predetermined direction.

It is also an object of this invention to provide an automobile door latch adapted to be latched against operation, and also unlatched by the operation of one of the latch operating handles.

It is another object of this invention to provide an automobile door latch wherein the inner handle is adapted to be operated to not only retract the latch bolt but to move the outer handle latch bolt retracting member out of effective retractive engagement with the latch bolt so that the operation of the outer handle will not cause a retraction of said latch bolt.

It is a further object of this invention to provide a vehicle door latch wherein the outer handle latch bolt retracting mechanism is adapted to be moved into an inoperative position by the operation of the inner handle mechanism in a direction opposite to the normal direction of movement of said inner handle for the purpose of retracting the latch bolt.

It is furthermore an object of this invention to provide a vehicle door latch wherein the inner and outer handles are controlled by a single spring which acts on the inner and outer handle retracting members to hold the

handles in their normal positions when the latch bolt is partly projected.

It is a further object of this invention to provide a door latch wherein the inner handle roll-back is adapted to be operated in a pre-determined direction to co-act with the outer handle roll-back or latch bolt retracting member to render the same inoperative with respect to the actuation of the latch bolt, said roll-back members of the inner and outer handles being controlled by a single spring which not only acts to latch the inner and outer handle roll-back member in a latching position, but also serves as a means for returning the outer handle roll-back or latch bolt retracting member into normal retracting engagement with the latch bolt.

It is an important object of this invention to provide a vehicle door of comparatively inexpensive construction adapted to render the operation of the outer handle effective or ineffective in causing retraction of the latch bolt, by simply operating the inner handle in a direction opposite from the normal latch bolt retracting direction of movement.

Other and further important objects of this invention will be apparent from the disclosures in the specification and the accompanying drawings.

This invention (in a preferred form) is illustrated in the drawings and hereinafter more fully described.

On the drawings:

Figure 1 is a plan view of an automobile door latch embodying the principles of this invention.

Figure 2 is an enlarged interior view of the door latch with the casing removed and showing the operating mechanisms in normal position.

Figure 3 is a similar view of the interior of the door latch showing the position of parts when the outer handle is actuated to move the latch bolt into a retracted position.

Figure 4 is a view similar to Figure 2 showing the inner handle cam or roll-back moved into a position to position the outer handle retracting member in an inoperative position and simultaneously set a key lock controlled mechanism in a position to return

the inner handle cam or roll-back into normal position by the use of a key from the exterior of the door.

Figure 5 is an enlarged detailed transverse section of the automobile door latch taken on line V—V of Figure 1.

Figure 6 is a transverse detail section taken on line VI—VI of Figure 2.

Figure 7 is a plan view of the interior of a modified form of automobile door latch equipped with a remote control mechanism.

Figure 8 is a transverse detail section taken on line VIII—VIII of Figure 7.

As shown on the drawings:

The improved vehicle door latch comprises a mounting plate or back plate 1, one end of which is bent at an angle to afford a flange 2 having a latch bolt opening therein. Secured in a boss or stud 3 formed on the mounting plate 1 is the inner end of a heavy coiled spring 4, the outer end of which projects to engage against a lug or shoulder 5 which is struck from or formed on a latch bolt extension arm or bar 6 which is slidably mounted longitudinally of the mounting plate 1 between guide lugs or flanges 7 and 8. The guide flanges 7 and 8 are struck inwardly in parallel planes from a cover plate or casing 9 which is secured to the mounting plate 1 to enclose the operating mechanisms of the latch. Secured to one end of the latch bolt extension bar or shank 6 is a latch bolt head 10 which is adapted to slidably project through an opening in the mounting plate flange 2. Integrally formed on the upper margin of the inner end of the latch bolt extension 6 is an arm 11 which is slidable beneath the guide flange 7. Also integrally formed on the lower margin of the inner end of the latch bolt extension 6 is a stop shoulder 12 which is adapted to contact against the guide flange 8 for the purpose of limiting the outward movement of the latch bolt head 10 and the latch bolt extension 6. Integrally formed on the upper margin of the latch bolt extension 6 between the arm 11 and the lug 5 is an upwardly projecting finger or lug 13 for a purpose hereinafter more clearly described.

Rotatable in an opening in the mounting plate 1 is a boss formed on the outer end of an inner handle roll-back 14 positioned to normally have one edge thereof in contact with the latch bolt extension arm 11, as clearly shown in Figure 2. The roll-back 14 is provided with a square opening 15 for the purpose of receiving the squared inner end of a stem of an inner handle (not shown).

Integrally formed on the inner handle roll-back is a locking or latch cam 16 which carries a lock pin 17 projecting from one side thereof. Also integrally formed on the inner handle roll-back 14 is a finger or projection 18 which is normally directed down-

wardly adjacent one side of the latch bolt extension 6.

Engaged around a pin 19 secured on the mounting plate 1 is the middle looped portion 20 of a handle control spring having one arm 21 thereof bent to afford a hump at 22, and an indented or curved portion at 23. The hump portion of the spring arm 22 is adapted to co-act with the inner handle latch cam 16, as illustrated in Figures 2 and 3. The handle control spring is provided with a second arm 24 the end of which is bent to hook around a pin 25 secured at right angles in a bifurcated or forked outer handle retracting member 26. The spring arm 24 acts to hold the lower edge of the outer handle retracting member 26 in its normal operative position in engagement with the finger 13 of the latch bolt extension. One end of the outer handle retracting member 26 is pivotally engaged on a pin 27 secured on the outer end of an outer handle roll-back or crank arm 28, the hub portion of which is provided with a suitable boss which is pivotally engaged in an opening of the mounting plate 1. The hub portion of the outer handle roll-back 28 is provided with a squared opening 29 for the purpose of receiving the squared inner end of a stem of an outer door handle 30 which is illustrated in dotted lines in Figures 2 and 3.

For the purpose of limiting the throw of the inner handle latch cam 16 a stop pin 31 is engaged at right angles in the mounting plate 1 against which the latch cam 16 is adapted to abut when the inner handle is actuated in a direction opposite to the normal direction of movement thereof for the purpose of moving the outer handle retracting member into an inoperative position.

Also supported on the mounting plate 1 is a pin 32 on which a bell crank is pivotally mounted. The short arm 33 of the bell crank is directed upwardly and has a rounded head which co-acts with the finger or projection 18 of the inner handle roll-back. The long arm 34 of the bell crank is provided with a notched or bifurcated head 35, the notch portion of which is engaged on a pin 36 secured at right angles on a crank arm 37. The crank arm 37 is supported on the inner end of a barrel 38 of a key lock which is mounted on the mounting plate 1 and is adapted to receive the key for the purpose of unlocking the automobile door latch from the exterior of the vehicle.

Figures 7 and 8 illustrate an automobile door latch of a construction similar to that illustrated in Figures 1 to 6 inclusive. In the modified form of construction, however, the latch bolt extension 6 is provided with a longitudinal opening 39. The inner and outer handle mechanisms and the latch bolt mechanisms have the various parts thereof numbered by reference numerals similar to those viewed in connection with Figures 1 to 6.

to 6 of the drawings. In this form of automobile door latch a remote control mechanism is associated with the door latch, and embraces a longitudinally positioned bar or plate 40 slidably mounted adjacent one side of the latch bolt extension 6 upon the guide flange 8. Struck from the slide bar 40 is a guide lug 41 leaving a notch 42 in the slide bar 40 into which the downwardly projecting finger or lug 18 of the inner handle roll-back projects. Secured through the slide bar 40 is a pin 43 the head of which is slidably engaged in the longitudinal slot 44 provided in the mounting plate 1. The pin 43 moving in the guide slot 44 acts to afford a means for limiting the sliding movement of the slide bar 40 with respect to the mounting plate 1. Secured to the pin 1 adjacent slide bar 40 is the inner end of a remote control connecting rod or bar 45 the outer end of which projects from the door lock casing 9. Pivottally connected to the outer end of the remote control connecting bar 45 is one end of a crank arm 46 the other end of which is provided with a hub portion 47 adapted to receive the stem of a remote control handle (not shown). The remote control handle may, of course, be located in any desired position on the inner side of preferably one of the front doors of the vehicle so that operation thereof will release the inner handle roll-back and permit the outer handle retracting member to drop back into operative co-acting position with the latch bolt extension 6.

35 The operation is as follows:

In the form of door latch illustrated in Figures 1 to 6 inclusive, the main control spring 4 presses against the lug 5 of the latch bolt extension and acts to normally hold the 40 latch bolt head 10 in its projected latching position. The improved latch is adapted to be mounted in a vehicle door in the usual position and manner to permit the projecting latch bolt head 10 to project into an opening in a door frame strike plate to hold the door rigidly in place in the door frame.

45 When the door is in normal closed position the latch bolt head is projected and the handle control spring 21-24 serves the dual 50 purpose of resiliently holding the inner handle roll-back in normal contacting position with the latch bolt extension arm 11 and the outer handle retracting member 26 in co-acting relation with the finger 13 of the latch bolt extension 6.

With the parts in the position illustrated 55 in Figure 2 the closed door may be readily opened from the exterior of the vehicle by simply turning the outer handle 30 into the 60 dotted line position illustrated in Figure 3, thereby causing the outer handle roll-back 28 to slide the outer handle retracting member 26 inwardly against the action of the spring arm 24. Inward movement of the retracting member 26 causes the lower finger or

70 tine thereof to act against the latch bolt extension finger 13 to slide the latch bolt extension 6 inwardly into the position shown in Figure 3, thereby retracting the latch bolt head 10 out of engagement with the opening 75 in the strike plate of the door frame. When this operation takes place the main control spring 4 is of course compressed ready to project the latch bolt head 10 outwardly into normal position as soon as the outer handle 80 30 is released. With the latch bolt head 10 retracted the vehicle door may be swung outwardly into open position and the outer handle released, as stated, to permit the latch bolt to be projected outwardly by the action 85 of the spring 4. Return of the latch bolt to normal position also causes return of the retracting member 26, the outer handle roll-back 28 and the outer handle 30 to their normal positions.

When the outer handle is operated to cause retraction of the latch bolt the inner handle 90 remains undisturbed in its normal position. The door when closed may also be opened from the interior of the automobile. This is done by operating the inner handle to cause the inner handle roll-back 14 to engage against the slide bar extension arm 11 to move the latch bolt head 10 and the latch bolt extension 6 inwardly against the action of the 95 control spring 4. When the inner handle is operated to retract the latch bolt the outer handle mechanisms are undisturbed. With the release of the inner handle after the opening of the door the control spring 4 acts to 100 automatically return the inner handle to its normal position, and, furthermore, serves to slide the latch bolt outwardly into its normal position.

105 The improved door latch is constructed to permit the inner handle mechanism to move the outer handle retracting member 26 into a release or inoperative position with respect to the latch bolt extension finger 13. This operation may take place when the door is 110 either in closed or in open position. To move the outer handle retracting member 26 into a released position the inner handle is operated in a direction opposite its normal direction of operation. This movement of the 115 inner handle causes the inner handle roll-back 14 to be moved from the position illustrated in Figure 1 into the position illustrated in Figure 4 thereby simultaneously causing the pin 17 on the inner handle latch 120 cam 16 to raise the forked end of the outer handle retracting member 26 so that the lower finger of said retracting member is moved out of co-acting engagement with the latch bolt retracting finger 13. As this operation takes place the extension or finger 18 on the inner handle roll-back co-acts with the rounded head of the short bell crank arm 33 to swing the bell crank 33-34 about the pivoted pin 32 into the position shown in 125 130

Figure 4 whereby the forked head 35 of the bell crank acting on the pin 36 causes the crank arm 37 to swing downwardly from its normal horizontal position. This movement of the crank arm 37 actuates the key lock mechanism 38 to lock the same. In the above mentioned position of the lock parts the outer handle retracting member 26, and the outer handle are ineffective in causing retraction of the latch bolt mechanism, since operation of the outer handle will merely cause the outer handle retracting member 28 to slidably move over the upper edge of the latch bolt extension finger 13. As the inner handle roll-back 14 is moved into the position illustrated in Figure 4 the latch cam 16 is moved into contact with the stop pin 31 thereby limiting the movement of the inner handle roll-back and the inner handle. As the inner handle roll-back is moved into a latching position to raise the outer handle retracting member 26 into an inoperative position, the cam edge of the cam member 16 co-acts with the hump and the curved portion 23 of the spring arm 21 to afford a resilient latching means whereby the inner handle roll-back is latched in a set position of adjustment. When the inner handle has been operated to set the parts, as illustrated in Figure 4, the door may be closed to permit the latch bolt head 10 to engage in the opening of the door frame strike plate to hold the door latched in position against release by the outer handle mechanisms. It will, of course, be understood that when the outer handle mechanism is moved into a position that is ineffective in causing retraction of the latch bolt mechanism that the inner handle mechanism may of course be operated at any time from the interior of the vehicle to cause retraction of the latch bolt mechanism and return of the outer handle retracting member 26 into its normal operating position by the action of the compressed spring arm 24.

In this type of door latch it will be noted that the latch bolt and the inner handle are always free to be operated from the interior of the car, and that the outer handle mechanisms are the parts which may be latched or moved into inoperative position.

It will thus be noted that all of the doors of an automobile, with the exception of one, may be latched against opening by operation of the inner handle mechanisms. The last or fourth door of the vehicle is equipped, as described, with a key release mechanism so constructed that the owner of a car may unlock the key lock 38 by means of a key, thereby causing the crank arm 37 to be swung upwardly from the position shown in Figure 4 into the position shown in Figure 2 to return the bell crank member 33-34 into its normal position. When this is done the short bell crank arm 33 co-acting with the exten-

sion or finger 18 of the inner handle roll-back causes the inner handle roll-back to be returned from the position shown in Figure 4 to the normal position shown in Figure 2 in co-acting engagement with the latch bolt extension arm 11. As this operation takes place the outer handle retracting member 26 is, of course, released and the spring arm 24 moves said retracting member 26 into normal engagement with the latching bolt retracting finger 13. The outer handle may now be operated to cause retraction of the latch bolt 10 so that the fourth door of the automobile may be opened from the exterior of the car. The remaining doors of the car of course may be released by simply operating the inner handles of the respective doors in a door opening direction thereby causing the respective inner handle roll-backs to be moved from their latching positions back into their normal positions into co-acting relation with the latch bolt arms 11 to retract said latch bolts permitting opening of the doors from the interior of the car.

In the modified form of the improved automobile door latch illustrated in Figures 7 and 8, the construction and operation of the latch and inner and outer handle mechanisms is similar to that already described. In this form of the device, however, the inner handle may be omitted and the latch bolt retracted from the interior of the car by means of a remote control mechanism which may be located in any convenient desired position within the car so that operation of the remote control handle will actuate the crank 46 and the connecting bar 45 to cause sliding movement of the slide bar 40, the lug or projection 41 of which acting in the opening 39 will cause retraction of the latch bolt 10. In this form of the device the latch bolt, of course, may also be retracted by operation of the outer handle mechanism.

Operation of the remote control handle in a direction opposite to the normal direction of operation will cause the slide bar 40 to move in a direction to co-act with the inner handle extension 18 to swing the inner handle roll-back into a latching position causing the pin 17 to raise the outer handle retracting member 26 into a release or inoperative position with the spring arm 21 lockingly engaging the latch cam 16 and the inner handle roll-back 14 in a set position of adjustment. The outer handle mechanisms and the inner handle roll-back of course may be moved back into normal position by swinging the remote control handle in its normal direction.

It will, of course, be understood that if desired the remote control door-latch mechanism illustrated in Figure 7, may be provided with a key lock release mechanism similar to that shown in Figure 4 to permit the remote control lock mechanism to be released from the exterior of the car by means of a

key. In this adaptation of the device the short bell crank arm 33 may be positioned to co-act with the inner end of the remote control slide bar 40.

5 I am aware that many changes may be made, and numerous details of construction may be varied through a wide range without departing from the principles of this invention, and I therefore do not purpose limiting 10 the patent granted hereon, otherwise than necessitated by the prior art.

I claim as my invention:

1. An automobile door latch comprising a latch bolt, a main spring for holding the same projected into latching position, an outer handle retracting member, an outer handle roll-back pivotally connected thereto, an outer handle adapted to actuate the outer handle roll-back and said outer handle retracting member to cause retraction of the latch bolt, a second spring connected with said outer handle retracting member to resiliently hold the same in co-acting relation with the latch bolt, an inner handle roll-back, a 25 cam integrally formed thereon and co-acting with said second spring, an inner handle adapted to be operated in one direction to operate said inner handle roll-back to cause retraction of the latch bolt, said inner handle 30 adapted to be operated in an opposite direction to move the outer handle retracting member into an inoperative position and simultaneously cause the second spring to lockingly hold the inner handle roll-back in 35 a set position of adjustment, and a key operated mechanism in said lock adapted to be set by the reverse movement of said inner handle roll-back to permit a key to release the same and said inner handle roll-back permitting the second spring to return the outer 40 handle retracting member into normal engagement with the latch bolt to again permit retraction of the latch bolt by the operation of the outer handle.

45 2. An automobile latch comprising a latch bolt, a main spring for controlling the operation thereof, an inner handle roll-back adapted to be operated in one direction to cause retraction of said latch bolt, an outer handle roll-back, an outer handle retracting member pivotally connected thereto and co-acting with said latch bolt to cause retraction thereof, a cam extension on said inner handle roll-back co-acting with said outer handle 50 retracting member, a spring co-acting with both said outer handle retracting member and said inner handle roll-back to hold the same in normal co-acting relation with said latch bolt, an extension on said inner handle 55 roll back, a bell crank co-acting with said extension, a crank arm co-acting with said bell crank, and a key operated mechanism for actuating said crank arm.

60 3. A vehicle door latch comprising a casing, a spring controlled latch bolt movably

mounted therein, an outer handle mechanism co-acting with said latch bolt to permit retraction thereof, an inner handle mechanism co-acting with said latch bolt to permit retraction thereof, said inner handle mechanism co-acting with said outer handle mechanism and adapted to move said outer handle mechanism into an inoperative position when the inner handle mechanism is moved in a direction opposite to its normal direction of movement, a spring in said casing co-acting with said outer handle retracting mechanism and with said inner handle retracting mechanism, and a key operated mechanism adapted to be set by the operation of said inner handle mechanism when the same is moved in a direction opposite to the normal direction of movement thereof, said key operated mechanism adapted to be released by means of a key to return the inner handle mechanisms and said outer handle mechanisms to their normal positions.

65 4. A latch comprising a casing, a spring controlled latch bolt slidably mounted therein, an outer handle mechanism co-acting with said latch bolt to permit retraction thereof, an inner handle mechanism co-acting with said latch bolt and with said outer handle mechanism, a spring in said casing co-acting with said outer handle mechanism and with 70 said inner handle mechanism, and a key operated mechanism in said casing co-acting with said inner handle mechanism adapted to be operated to permit return of said inner handle mechanism and said outer handle mechanism 75 to their normal positions.

80 5. In a latch the combination with a spring controlled latch bolt, of co-acting inner and outer handle mechanisms adapted to be independently operated to cause retraction of said latch bolt, resilient means co-acting with said inner and outer handle mechanisms to hold the same in resilient contact with said latch bolt, said inner handle mechanism 85 adapted to be operated in one direction to cause retraction of the latch bolt, and in an opposite direction to cause the outer handle mechanism to be moved out of operative relation with said latch bolt, and a key releasable mechanism co-acting with said inner handle mechanism adapted to be set when said inner handle mechanism is moved into a position to cause the outer handle mechanism to be moved into an inoperative position.

90 6. A door latch comprising a casing, a 105 spring controlled latch bolt slidably mounted therein, an inner handle mechanism co-acting with said latch bolt, a bifurcated outer handle mechanism co-acting with said latch bolt and with said inner handle mechanism, and a 110 spring co-acting with said bifurcated outer handle mechanism and with said inner handle mechanism adapted to resiliently hold said bifurcated outer handle mechanism and said inner handle mechanism in co-acting relation 115

with said latch bolt, and further adapted to hold said inner handle mechanism in a locked position of adjustment when said inner handle mechanism is operated to move the bifurcated outer handle mechanism into an inoperative position with respect to said latch bolt.

7. A door latch comprising a casing, a spring controlled latch bolt slidably mounted therein, an outer handle mechanism in said casing adapted to be operated to cause retraction of the latch bolt, a key operated mechanism in said casing, and an inner handle mechanism within said casing co-acting with said latch bolt, with said outer handle mechanism and with said key operated mechanism, said inner handle mechanism adapted to be moved in one direction to cause retraction of the latch bolt and to be moved in an opposite direction to simultaneously cause movement of said outer handle mechanism into an inoperative position with respect to the latch bolt, and setting of said key operated mechanism to permit the same when released by a key to return the inner handle mechanism and said outer handle mechanism to their normal positions.

8. The combination with a spring controlled latch bolt, of an inner handle mechanism and an outer handle mechanism co-acting with one another and with said latch bolt, a spring for holding said inner and outer handle mechanisms in co-acting relation with said latch bolt, and a key operated mechanism co-acting with said inner handle mechanism, said inner handle mechanism adapted to be operated in one direction to cause retraction of the latch bolt and in an opposite direction to cause simultaneous release of said outer handle mechanism and setting of said key operated mechanism.

In testimony whereof I have hereunto subscribed my name.

BAYARD E. TAYLOR.
